UNITED STATES PATENT OFFICE.

MARTIN A. SMITH, OF ATLANTIC, IOWA.

BAND-CUTTER AND FEEDER.

SPECIFICATION forming part of Letters Patent No. 426,077, dated April 22, 1890.

Application filed December 20, 1889. Serial No. 334,380. (No model.)

To all whom it may concern:

Be it known that I, MARTIN A. SMITH, a citizen of the United States, residing at Atlantic, in the county of Cass and State of Iowa, have invented certain new and useful Improvements in Band-Cutters and Feeders; and I do declare the following to be a full, clear, and exact description of the invention, such as will enable others skilled in the art to which it appertains to make and use the same.

This invention has relation to improvements in band-cutters and feeders for thrashing-machines, and the novelty will be fully understood from the following description and claims, when taken in connection with the accompanying drawings, in which—

Figure 1 is a perspective view of the box or casing containing my improved mechanism for feeding and cutting bundles of grain. Fig. 2 is an inverted plan view of the same. Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Referring by letter to said drawings, A indicates a box or casing, which is designed to receive and inclose the operating mechanism.

Fig. 2 is an inverted plan view of the same. Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same. Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

Fig. 2 is an inverted plan view of the same.

Fig. 3 is a vertical cross-sectional view. Fig. 4 is a view of the knife removed. Fig. 5 is a side view of one of the feeder-bars carrying fingers; and Fig. 6 is a cross-sectional view of one of the feeder-bars, taken in the plane indicated by the line $y y$ of Fig. 5.

one end of a double-crank shaft F. This double-crank shaft has its bearings in cross bars or strips e, and also carries about midway of its length a fixed beveled gear f, which meshes with a similar beveled gear g, the latter being arranged on a shaft G, to the outer end of which is fixed a wheel H, which is eccentrically connected with one end of the knife or cutter I, the opposite end of said knife being connected with a pivoted arm K, which latter is connected with the fixed bar or strip e, so that the knife may be allowed a vertical reciprocating movement. It is obvious that instead of having a wheel, such as H, on the shaft G the said shaft may be cranked at that point and connected with the cutter, so as to impart the desired movement thereto.

Journaled in the bearing-strips e is a double-crank shaft L, which is arranged parallel to the double-crank shaft F, and the crank portions of these two shafts are connected by the feeder-bars M, so that when the shafts are rotated the crank portions thereof will impart a vertical reciprocation to the feeder-bars. These crank-shafts are also provided at opposite points with fixed chain-wheels h, and said wheels are connected by an endless chain N, so that when the crank-shaft carrying the beveled gears has been rotated the chain wheels and belts will impart a corresponding rotary movement to the crank-shaft L, and consequently a vertical reciprocation to the feeder-bars.

From the construction illustrated it will be seen that the movement of the feeding mechanism and the cutting mechanism is synchronous and that both are geared with a common power-shaft. It will also be seen that all of the mechanism is hidden from view and protected from injury by being inclosed within the box or casing A.

The feeder-bars M, which are provided with eyes near opposite ends to receive the crank portions of the shafts F and L, are preferably beveled on opposite sides at their upper longitudinal edges, as shown at i, so that they may partly enter the slots a in the top of the casing, and these beveled edges are provided with a suitable number of vertically-disposed pins or studs l, which are designed to pass through the slots at each reciprocation of the

bars and feed the bundles toward the knife or cutter.

The knife I, I have shown as provided with teeth, which are designed to pass up through the slot *b* to cut the rope or cord of a bundle; but it is obvious that any suitable form of cutter might be employed.

Secured to opposite sides of the case or box A are vertical standards P. These standards are provided with longitudinal slots *m*, whereby the same may be vertically adjusted and secured at any desired position to the casing. Journaled in the upper ends of these standards is a horizontal cross-bar Q, to which is secured a shield and presser, which will be presently explained. This shaft Q, which is journaled in the standards P, so that it may turn therein, has secured to one or both of its ends a movable arm R. This arm R, which depends from the end of the shaft Q and is fixed thereto, passes through a guide *r* in the side wall of the casing, and has its lower end connected with a spiral or coil spring S, the opposite end of said spring being suitably secured, so that the lower end of the arm R will be drawn rearwardly and the shield or presser secured to the shaft normally held in a depressed position. Secured to this partially-rotatable shaft Q are forwardly-curved arms *t*, which extend beyond the slot *b* in the box or casing for the passage of the cutter, and secured to these arms *t* is a plate T of sheet metal or other suitable material, a slot or interspace *u* being left in the plate or shield above the slot *b* in the casing, as shown, so that in operation the knife may not strike the said plate. By this construction it will be seen that we have a shield or presser which may be vertically adjusted with respect to the box or casing, and which will press upon the bundle with sufficient elasticity to hold the same in proper position while the band is being cut. It will also be seen that this presser-plate is higher at the entrance end of the bundle, so as to facilitate the introduction of the latter.

In operation, when the presser or shield has been set at the desired position and motion has been imparted to the shaft C by a belt from the thrasher, such motion will be imparted through the medium of the bevel-gear to the double-crank shaft F and simultaneously

therefrom through the bevel-gearing *f* and *g* and the chain N and wheels fixed to said crank-shaft to the cutter and feeder bars, respectively. Thus when a bundle is placed upon the top of a box or casing it will be carried through the action of the feeder-bars and their fingers beneath the presser and over the knife-slot, where the said bundle will be held in position while the band of the bundle is being severed. The next bundle being moved by the feeder-bars or their fingers will force the cut bundle away from the knife and place the uncut one in a position to receive the blade.

Having described my invention, what I claim is—

1. In a band-cutter and feeder, the combination, with the box or casing, of the main drive-shaft having a bevel-gear at one end, the double-crank shaft having a bevel-gear meshing with the gear on the power-shaft, the gear *f*, secured to said crank-shaft, the knife-shaft having a wheel at one end to connect with a knife and a bevel-gear at its opposite end, the double-crank shaft L, the chain-wheels and endless chain connecting the crank-shafts, and the feeder-bar carrying pins and secured to the crank portion of the shafts, substantially as specified.

2. The combination, with the box or casing, of the vertically-adjustable standards secured thereto, the shaft Q, journaled in said standards, the forwardly-curved arm secured to the shaft, the slotted plates secured to the arms, the arm secured to one end of the shaft, the stop-guide on the side of the casing and receiving said arm, and the spring connecting the lower end of the arm to the casing, substantially as specified.

3. In a band-cutter and feeder, the combination, with the box or casing, of the slotted standards vertically adjustable thereon, a presser formed with a slot and journaled in the standard, and an arm having its upper end fixed to the shaft of the presser and its lower end yieldingly connected to the casing, substantially as described.

In testimony whereof I affix my signature in presence of two witnesses.

MARTIN A. SMITH.
